UNITED STATES PATENT OFFICE.

CHARLES HUNT, OF WASHINGTON, DISTRICT OF COLUMBIA.

DETACHING GEAR.

Application filed May 17, 1923. Serial No. 639,598.

To all whom it may concern:

Be it known that I, CHARLES HUNT, a citizen of the United States, residing at Washington, District of Columbia, have invented certain new and useful Improvements in Detaching Gears, of which the following is a specification.

This invention relates to an improved detaching gear, especially adapted for use on life boats or other similar conditions where the load is connected in a plurality of places and must be released simultaneously at all points.

The objects being to provide a detaching device wherein the supporting member is locked against accidental movement and release of the load by the weight of the load.

A further object being to positively operate the supporting member in both directions to further insure against accidental movement of the parts.

A further object being to provide the above and means for simultaneously releasing the load from a single place on the load in a simple, durable and inexpensive manner.

The above and other objects in view will appear in the description and be finally pointed out in the appended claims.

Similar numerals indicate corresponding parts in all the figures of the drawings in which:

Figure 1 is a longitudinal section of a life boat showing my improved releasing mechanism.

Figure 2 is a plan view of the parts shown in Figure 1.

Figure 3 is a detail side view, partly in section, of the detaching gear.

Figure 4 is a front view of the parts shown in Figure 4.

Figure 5 is a vertical section on line 5-5 of Figure 3.

Figure 6 is a view of the mounting member when used on metal steam boats.

Reference now being had to the drawings by numerals, 1 indicates the conventional form of life boat having mounted on its stem and stern posts detaching gear 2-2 of identical construction.

The detaching gears 2-2 are operated by releasing means extending preferably along the side of the boat from its ends to a point that is conveniently located where the operating means is mounted to operate the

detaching gears at the ends of the boat simultaneously by a single movement.

One of the detaching members is shown in detail in Figure 3 and consists of a casting or forging 3 having the vertical mounting portion 4, provided with perforations 5 through which securing means such as cap screws may pass to firmly secure the device to the stem or stern post of the boat.

From the rear or securing plate 3, a horizontal portion 6 extends from which ears 7 and 8 extend in an upward direction from either side of the member 6. From the outer edges of plate 6 bracket shaped braces 9 extend and form an integral part of the body of the detaching member.

Pivots mounted on a pin 10 between the upwardly extending ears 8 is a boat line ring 11 having the enlarged portion 12 adapted to fill the space between the ears.

Pivots mounted between the upwardly extending ears 7 is a rocking or holding arm 13, mounted near its center on pin 14 and provided with the extension 15 over which the ring 15' of the boat lowering tackle is adapted to engage.

The rocker arm 13 is also provided with a bifurcated extension 16 in which is pivots mounted on pin 17, the upper end of a toggle or locking lever 18.

The locking lever 18 is provided with an inwardly projecting lug 19 so located as to rest, when the parts are in their set or holding position, directly above a shoulder 20 at the outer end of plate 6.

The bracket members 9-9 beneath the plate 6 extend out beyond said plate as shown at 21-21. Between the outer ends of the extensions 21-21 is an operating or tripping lever 22 pivoted on pin 23. Said lever 22 is pivots intermediate its ends, the upper end being pivots mounted to the lower end of locking arm 18, by pin 24 and the lower end being connected with the tripping and setting or retaining cables.

Rotatably mounted on pin 25, between the members 9-9, is an idler 26 over which the tripping cable is drawn. The detaching gears as described are mounted at the ends of the boat and are adapted to receive over the holding bars 15 the rings of the lowering tackle in a well known manner.

Located preferably near the center of the boat is the means for tripping the detaching gears and consists of a drum 27 mount-

ed on a bracket 28^a, secured to the side of the boat. Over said drum pass the tripping and setting or retaining cables 28 and 29 respectively.

5 As shown in Figure 1, the tripping cable from the stern of the boat passes around beneath the drum while the corresponding cable from the bow of the boat passes over the top of the drum and they are secured at 10 their outer ends, after passing around the idler 26, to the operating levers 22. The setting or retaining cables pass in opposite directions around the drum to their associated tripping cables, and are secured 15 directly to the operating levers, thus providing for a single movement of the drum by the lever 40 in one direction to release both ends of the boats simultaneously, by drawing on the tripping cables, while at 20 the same time slackening off on the setting or retaining cables to permit movement of the operating lever.

The cables preferably run over pulleys 41 and through supporting eyes 42 along 25 the side of the boat and pass around pulleys 43 and then about pulley 44 and finally in a direct pull to the detaching gear.

The operation is obvious and consists in supporting the boat on the holding bars 30 15 at the ends of the boat during the lowering of same, and when it is desired to release the boat, lever 40 may be swung over, cables 28—28 will operate lever 22 to trip the locking lever 18 and rock the holding 35 arm 13 from which the tackle may readily slip and release the boat. Should the weight be too great for the pins 24 or 23 and they should shear off, shoulder 19 will drop to lug 20 and the holding bar will 40 still maintain its position and the boat will not be dropped.

Having thus described my invention, what I claim and desire to secure by Letters Patent is:

45 1. A boat releasing device, comprising a body portion, a holding bar journaled in the body and adapted to hold a member of the launching tackle, a locking lever, provided with a safety lug, an operating lever, and means for positively operating the operating lever to release or engage the tackle.

55 2. A boat releasing device, comprising a body portion, a stop lug, a holding bar journaled in the body and adapted to hold a member of the launching tackle, a locking lever provided with a safety lug adjacent to said stop lug, an operating lever, and means for positively operating the operating lever to release or engage the tackle.

60 3. A releasing device comprising a pivotal holding bar, pivoted releasing means, and automatic means for preventing release upon fracture of the pivots of 65 the releasing means.

4. A releasing device comprising a frame for mounting, a pivoted holding bar, a stop on the frame, a locking lever secured to the bar, a lug on the locking lever adapted to rest adjacent to the stop in locked position, a pivoted operating lever adapted to operate the locking lever, and means for swinging the operating lever.

5. A releasing device comprising a frame for mounting, a pivoted holding bar, a stop 70 on the frame, a locking lever secured to the bar, a lug on the locking lever adapted to rest adjacent to the stop in locked position, a pivoted operating lever secured at one end to the locking lever, and means 80 secured to the opposite end of said operating lever to swing said lever and operate said locking lever.

6. A releasing device comprising a frame for mounting, a holding bar, a locking lever pivoted to the holding bar, and a pivoted operating lever pivoted to the locking lever, said pivots being out of alignment when 85 in locked position.

7. A releasing device comprising a frame 90 for mounting, a pivoted holding bar, a stop on the frame, a locking lever pivoted to the holding bar, and a pivoted operating lever pivoted to the locking lever, said pivots being so arranged as to automatically 95 retain the holding bar locked in its holding position.

8. The combination with a life boat, supported at either end of releasing means, consisting of holding bars adapted to receive the lowering tackle, locking levers pivoted to the holding bar, operating levers pivoted to the locking levers, cables secured to the operating levers and adapted to operate the levers in corresponding directions, 100 105 simultaneously.

9. The combination with a life boat, supported at either end of releasing means, consisting of holding bars adapted to receive the lowering tackle, locking levers 110 pivoted to the holding bar, operating levers pivoted to the locking levers, cables secured to the operating levers and passing around a drum and adapted to operate the levers in corresponding directions, simultaneously.

10. The combination with a life boat, supported at either end of releasing means, consisting of holding bars adapted to receive the lowering tackle, locking levers 115 pivoted to the holding bar, operating levers pivoted to the locking levers, a drum having an operating bar, and cables extending from the operating levers in opposite directions and around the drum to provide 120 125 for the simultaneous operation of the releasing mechanism by the movement of the drum.

In testimony whereof I affix my signature.
CHARLES HUNT.
